UNITED STATES PATENT OFFICE.

FRED L. MILLS, OF OAK PARK, ILLINOIS, ASSIGNOR TO MILK NOVELTY COMPANY, OF CHICAGO, ILLINOIS, A CORPORATION OF ILLINOIS.

DESIGN FOR A FRONT PLATE FOR A VENDING-MACHINE CABINET.

Application filed July 25, 1927. Serial No. 22,865. Term of patent 14 years.

To all whom it may concern:

Be it known that I, FRED L. MILLS, a citizen of the United States, residing in Oak Park, in the county of Cook and State of Illinois, have invented a new and original Design for a Front Plate for a Vending-Machine Cabinet, of which the following is a specification, reference being had to the accompanying drawing, forming a part thereof.

In the drawing

The figure is a perspective view of a front plate for a vending machine cabinet showing my new design.

I claim:

The ornamental design for a front plate for a vending machine cabinet, as shown.

FRED L. MILLS

CERTIFICATE OF CORRECTION.

Design Patent No. 75,742.

Granted July 10, 1928, to

FRED L. MILLS.

It is hereby certified that the name of the assignee in the above numbered patent should have been written and printed as "Mills Novelty Company" instead of "Milk Novelty Company", as shown by the records of assignments in this office; and that said Letters Patent should be read with this correction therein that the same may conform to the record of the case in the Patent Office.

Signed and sealed this 21st day of August, A. D. 1928.

(Seal)

**M. J. Moore,
Acting Commissioner of Patents.**
